(57) **CLAIM**

The ornamental design for a ball projectile, as shown and described.

DESCRIPTION

FIG. 1 is a top front perspective view of the ball projectile showing a first embodiment or our new design;

FIG. 2 is a right side elevational view thereof;

FIG. 3 is a left side elevational view thereof;

FIG. 4 is a front view thereof;

FIG. 5 is a rear view thereof;

FIG. 6 is a top view thereof;

FIG. 7 is a bottom view thereof;

FIG. 8 is a top front perspective view showing a second embodiment or our new design;

FIG. 9 is a right side elevational view thereof;

FIG. 10 is a left side elevational view thereof;

FIG. 11 is a front view thereof;

FIG. 12 is a rear view thereof;

FIG. 13 is a top view thereof;

FIG. 14 is a bottom view thereof;

FIG. 15 is a perspective view showing a third embodiment or our new design;

FIG. 16 is a right side elevational view thereof;

FIG. 17 is a left side elevational view thereof;

FIG. 18 is a front view thereof;

FIG. 19 is a rear view thereof;

FIG. 20 is a top view thereof; and,

FIG. 21 is a bottom view thereof.

The broken lines shown are included for the purpose of delineating the bounds of the claim adjacent to the unshaded areas.

1 Claim, 12 Drawing Sheets
